UNITED STATES PATENT OFFICE.

EDWARD G. THOMAS, OF BOSTON, MASSACHUSETTS, ASSIGNOR TO LAMSON COMPANY, OF NEWARK, NEW JERSEY, A CORPORATION OF NEW JERSEY.

POWER CONTROL.

1,104,019.

Specification of Letters Patent. Patented July 21, 1914.

Application filed June 1, 1906. Serial No. 319,731.

To all whom it may concern:

Be it known that I, EDWARD G. THOMAS, of Boston, in the county of Suffolk and State of Massachusetts, have invented certain new and useful Improvements in Power Control, of which the following is a specification.

My invention relates to improvements in power control especially for apparatus for compressing or exhausting air or other fluids and is intended to provide a new and more efficient way of adjusting the work done by the pumping device to the amount of fluid required by the service to be performed.

It consists of switching devices located on one or both sides of the pump by which the current of fluid produced by it may be delivered to the storage tank of the operating system as long as the pressure therein is below a predetermined point and may be delivered to a receptacle containing a less pressure—such as the atmosphere in the case of air—whenever the predetermined pressure is exceeded in the storage tank.

The invention is of special value in connection with pneumatic tube systems where the air is furnished by a blower driven by an electric motor.

My invention provides a means whereby the blower may rotate at a constant speed doing no work beyond that required to overcome friction except when the reserve pressure is less than normal.

In the accompanying drawings which illustrate a construction embodying my invention, Figure 1 is a side elevation of the device in operating connection with a blower and a vacuum and pressure storage drum. Fig. 2 is an enlarged sectional elevation of the controlling mechanism showing the position of the parts when the blower is relieved of load on the pressure side. Fig. 3 is an enlarged sectional elevation of the controlling mechanism showing the normal position of the parts with the blower in operating connection with the vacuum storage drum.

Like letters of reference refer to like parts throughout the several views.

C and D are respectively a pressure and a vacuum storage drum connected to the blower B by the pipes C² and D². In the pipe C² is placed a switch or valve H consisting of a vane H' secured to a shaft H²

in rotational relation to the casing H; opposite to the connection between the casing H and the storage drum C, the said casing is connected to a pipe E which is open to the atmosphere through the ports E' and which for reasons which will be given later, extends beyond the ports E' to make a similar connection on the vacuum side of the apparatus to that which has been described for the pressure side. Mounted on the outer or projecting end of the shaft H² is a crank arm H³ connected with a piston rod F² by means of the link H⁴. Fixed to the piston rod F² is the piston F' reciprocally mounted within the cylinder F. The lower end of the piston rod F² extends through a bearing in the lower head of the cylinder F and carries the yoke F³ to which are attached at one end the tension springs F⁴, said springs being attached at the opposite end to the lower cylinder head of the cylinder F. The lower portion of the cylinder F is normally open to the atmosphere by holes F⁵ (Fig. 2). The pipe C³ connected at one end with the drum C is connected at the opposite end with the upper portion of the cylinder above the piston F' by a passage F⁶ controlled by the valve G attached to the diaphragm G', which diaphragm is inclosed by the cap G²; mounted in the head of said cap is the adjustable screw G³ secured in position by the check nut G⁴ and connected with the diaphragm by the spring G⁵. Said valve G normally holds the passage F⁶ open, the upper part of the passage F⁶ being connected with the atmosphere by a passage F⁷ controlled by a recess G⁶ in the valve G. This passage is normally closed by the valve G. The pipe C³ is connected with the outer diaphragm chamber G⁷ by the pipe G⁸. Controlling the communication of the pipe D² with the vacuum tank D is a similar switch and controlling mechanism adapted to be operated by vacuum and the operation of which is hereinafter fully described. The direction of the air currents is indicated by arrows.

X represents connections of outside apparatus (preferably pneumatic despatch tube apparatus) with the pressure drum C and the vacuum drum D.

The operation is as follows: The blower B driven by the motor A produces air currents in the directions indicated by the

arrows Fig. 1; this produces a vacuum in the drum D and a pressure greater than atmospheric in the drum C with the valves in normal position shown in Figs. 2 and 3; the pressure in the drum C passing through the passage F⁶ entering the upper part of the cylinder against the tension of the springs F⁴; this pressure also acts through the pipe G⁸ within the diaphragm chamber 10 G' and upon the diaphragm G' but is normally balanced by the tension of the spring G⁶. When the pressure in said drum rises above the predetermined point to which the diaphragm is adjusted, the diaphragm is forced inward closing the passage F⁶ by means of the valve G at the same time opening the upper part of the cylinder F by means of the passage F⁷ and recess G⁴ allowing the escape of the pressure within the cylinder. The springs F⁴ now force the piston upward and through the link H⁴ and crank H³ turn the balance valve H into the position shown in dotted lines F². The check-valve C' now closes and the current of air is diverted through the pipe E and apertures E' into the atmosphere. When the pressure in the tank C drops below normal the spring G⁶ causes the diaphragm and valve G to assume normal position opening the passage F⁶ causing the pressure to enter the cylinder, forcing the piston downward and causing the valve H to assume its normal position. The pressure now passes through the pipe C², pipe E, check valve C' 25 into the drum C.

In the mechanism shown in Fig. 3 controlling the vacuum drum D, the piston F' is held by the spring F⁴ at the lower part of the cylinder F. The vacuum communicating through the pipe D³ and passage G⁸ with the diaphragm chamber G' acts upon the diaphragm G' and is normally balanced by the spring G⁶. When the vacuum exceeds the normal, the diaphragm is drawn outward causing the valve G to close the passage F⁷ to the atmosphere and open communication of the vacuum with the cylinder through the passage F⁶. The vacuum now draws the piston F' to the upper part 40 of the cylinder, causing the valve H to assume the position shown in dotted lines and open the blower to the atmosphere. When the vacuum decreases releasing the diaphragm G' the passage F⁶ is closed to the vacuum and opened to the atmosphere through passage F⁷ by means of the valve G causing the piston and valve H to assume normal position.

The pipe E is made continuous between 45 the pressure and vacuum valves in order that when both sides of the blower are connected to the atmosphere the air may pass from the pressure side directly to the vacuum side without the loss of power which 50 will occur if separate openings into the at-

mosphere are provided. This loss of power comes through the eddies produced by driving the discharged air directly into the atmosphere and re-collecting from the atmosphere the same volume at another point.

Either side of the blower can be relieved of load independently of the other by the action of the apparatus upon that side, saving the power otherwise required for the compression or expansion of the constant volume of air, and if the blower is used for a system requiring either pressure or vacuum alone, only that part of the apparatus which has to do with the control of the appropriate side of the blower need be installed, that is to say, either the pressure or the vacuum mechanism may be installed as the case requires.

This invention may be applied to any form of pumping machinery and mechanical equivalents may be substituted for any of the parts described.

Having thus described the nature of my invention and set forth a construction embodying the same, what I claim as new and desire to secure by Letters Patent of the United States is:

1. In an apparatus of the character described, a constantly operating blower, a pressure storage drum communicating with the pressure side of the blower, a vacuum storage drum communicating with the exhaust side of the blower, a pipe forming a communication between said drums and open to the external air at a point intermediate of its connections with the drums, and a valve mechanism controlling the communications of the pressure drum with the blower and pipe actuated by fluctuations of pressure in the pressure drum to direct the pressure from the blower to either the pressure drum or the pipe.

2. In an apparatus of the character described, a constantly operating blower, a pressure storage drum communicating with the pressure side of the blower, a vacuum storage drum communicating with the exhaust side of the blower, a pipe forming a communication between said drums and open to the external air at a point intermediate of its connections with the drums, and a valve mechanism controlling the communications of the vacuum drum with the blower and pipe actuated by fluctuations of the vacuum in the vacuum drum to direct the exhaust to the blower from either the vacuum drum or from the pipe.

3. In an apparatus of the character described, a constantly operating blower, a pressure storage drum communicating with the pressure side of the blower, a vacuum storage drum communicating with the exhaust side of the blower, a pipe forming a communication between said drums and open to the external air at a point inter-

mediate of its connections with the drums, a valve mechanism controlling the communications of the pressure drum with the blower and pipe actuated by fluctuations of pressure in the pressure drum to direct the pressure from the blower to either the pressure drum or the pipe, and a second valve mechanism controlling the communications of the vacuum drum with the blower and pipe actuated by fluctuations of the vacuum in the vacuum drum to direct the exhaust to the blower from either the vacuum drum or from the pipe.

4. A fluid pressure system, comprising a pump, a plurality of reservoirs, and means for automatically connecting and disconnecting each reservoir to and from the pump in response to the pressure of the fluid in that reservoir alone.

5. A fluid pressure system, comprising a pump, a plurality of reservoirs, and automatic means for independently connecting the pump to each reservoir when the fluid pressure in said reservoir departs from its normal value and disconnecting the pump from said reservoir when said pressure attains said normal value.

6. A fluid pressure system, comprising a pump, a plurality of reservoirs, means governed by the pressure in each reservoir for connecting said reservoir to the pump whenever said pressure departs from its normal value and disconnecting said reservoir from the pump when said pressure is restored to its normal value.

7. A fluid pressure system, comprising a pump, a plurality of reservoirs, means governed by the pressure in each reservoir for connecting said reservoir to the pump whenever the pressure therein departs from its normal value and disconnecting said reservoir from the pump when said pressure returns to said normal value, and a motor for

driving said pump whenever any reservoir is connected thereto.

8. In a fluid pressure system, an air pump, two reservoirs, a valve for connecting the intake side of the pump to one of the reservoirs or to the atmosphere, a valve for connecting the outlet side of the pump to the other reservoir or to the atmosphere, said valves being independent of said pump, and means for automatically controlling said valves in response to the pressures in the reservoirs.

9. In a fluid pressure system, an air pump, two reservoirs, a valve for connecting the intake side of the pump to one of the reservoirs or to the atmosphere, a valve for connecting the outlet side of the pump to the other reservoir or to the atmosphere, said valves being independent of said pumps, and fluid pressure responsive devices for automatically controlling said valves respectively in response to the pressures in the two reservoirs respectively.

10. A fluid pressure system, comprising a pump, two reservoirs, a device responsive to the pressure in one of said reservoirs for connecting the intake side of the pump to said reservoir when the pressure in the latter rises above a predetermined value, and a second device responsive to the pressure in the second reservoir for connecting the outlet side of said pump to said second reservoir when the pressure in the latter falls below a predetermined value, said devices being independent of said pumps.

In testimony whereof, I have signed my name to this specification in the presence of two subscribing witnesses, this twenty-sixth day of May, A. D. 1906.

EDWARD G. THOMAS.
